SIMEON S. JACKSON, OF BOSTON, MASSACHUSETTS, ASSIGNOR TO THE STAFFORD COMPANY, OF BOSTON, MASSACHUSETTS, A CORPORATION OF MASSACHUSETTS.

FILLING-FEELER MECHANISM FOR LOOMS.

Application filed October 11, 1923. Serial No. 667,834.

The invention has relation in general to the depletion-detecting mechanisms, commonly termed feeler mechanisms, which are employed in looms for the purpose of fore-stalling complete exhaustion of the supply of weft or filling contained in the working shuttle upon the lay-beam of a loom. These mechanisms in general are contrived to "call," or "indicate," or "initiate," as it is variously termed, a change in the operation of the loom, upon detecting that the progressive depletion of the said supply has reached a stage decided upon as a minimum. This change involves in some cases automatic replenishing of the working supply of the weft or filling without stoppage of the loom; in others it involves stoppage of the loom, with automatic replenishment during the stoppage, followed by automatic re-starting of the loom.

The invention has relation more especially to feeler mechanisms of the measuring class. A feeler mechanism of this class is arranged to call the aforesaid change in the operation of the loom in which it is employed, when, through its measuring action, it has detected that the residue of weft or filling upon the bobbin or other weft or filling-carrier in the shuttle has become reduced to the predetermined minimum thickness.

The object of the invention is to provide a measuring feeler mechanism of improved character, and of simple and durable construction; also reliable in operation.

The invention consists essentially in measuring filling-feeler mechanism having a filling-feeler member, a datum-surface-engaging member combined therewith, preferably arranged to cooperate with the front wall of a loom shuttle, moving forwardly and rearwardly with the filling-feeler member and adapted to swing transversely in a horizontal plane when acted upon by the datum-surface, a latch controller constituted by a bolt that is linked to the said datum-surface-engaging member and that controls the latch of the change-calling mechanisms vertically, and a spring operating to hold said bolt and datum-surface-engaging member in their normal positions with the latch out of the path of the actuator which cooperates therewith.

An illustrative embodiment of the invention is shown in the accompanying drawings, combined with certain loom parts of

well-known construction, only such loom parts being shown as are necessary to an understanding of the invention.

In the drawings,—

Fig. 1 is a plan view of portions of the lay-beam, breast-beam, and associated parts at one side of a loom, showing the said embodiment of the invention applied thereto, certain parts being in section.

Fig. 2 is a front view of one end of the breast-beam and parts associated therewith, with the said embodiment of the invention mounted in operative position thereon.

Fig. 3 is a view of the devices shown in Figs. 1 and 2, in section on line 3, 3, of Fig. 1, looking in the direction of the arrows.

Fig. 4 is a view in section on line 4, 4, of Fig. 1, looking in the direction of the arrows.

Figs. 5 and 6 are sectional details on lines 5, 5, and 6, 6, respectively, of Fig. 1, on a slightly larger scale than the preceding figures.

Having reference to the drawings,—

At 1 is the lay-beam, a shuttle 2 being represented as occupying the shuttle-box that is shown in Figs. 1 and 3, and a bobbin 3 with its wound mass of weft or filling 4 being illustrated as occupying said shuttle 2.

At 7 is the filling-engaging portion of a filling-feeler member 8 adapted to enter the shuttle through the usual slots 59 and 61 in the shuttle-box front-plate 5 and the front shuttle wall, respectively, as the lay comes forward in beating up. This filling-engaging member 8, and the means and manner of supporting the same, may vary in practice. Preferably, though not necessarily always in practice, the said member is, as shown, a slide mounted in guides 9 and 10 on a feeler-stand 11, and held rearward in its normal presentation position by the action of an expanding spiral spring 12 surrounding a rod-like reduced forward end-portion 81 of the feeler-slide, the said spring being confined between the forward guide 10 and a shoulder 13 upon the feeler-slide. The said normal presentation position is determined through contact of shoulders 14, 14, that project laterally from the slide with the forward end of guideway 9, as in Fig. 1. The feeler-slide 8 is retained in place within guide 9 by a cover-plate 15 overlying the feeler-slide and secured on guide 9 by screws 16, 16. As usual, the contact of the shuttle-contents

with the rear end-surface 71 of the portion 7 of the member 8 as the lay advances produces forward movement of the said member 8.

5 The datum-surface-engaging member comprises a lever 18 that is pivoted upon a stud 19 extending upward from the filling-feeler member 8, the said lever being held on said stud by a cotter-pin 20. As this lever is intended to receive a turning impulse, in this instance in a horizontal plane, from the forwardly moving datum-surface which acts thereagainst, in this instance the outer surface of the front wall of the shuttle body, 10 and to transmit a transverse movement to the controller-bolt 30 cooperating with the latch 33 of the change-calling mechanism, it is conveniently formed in the shape of a bell-crank, Figs. 1, 2, and 3, having an inwardly 15 projecting arm 22 provided with a shuttle-contacting tip 21, and a forwardly projecting arm 24 to which the latch-controlling bolt is linked by connections presently described herein. The shuttle-contacting tip 21 of the datum-surface-engaging member 20 is a screw which is screwed into a hole in the inwardly projecting arm 22 of lever 18, with its contacting end projecting rearwardly from said arm, the said screw being secured in adjusted position by the lock-nut 23.

The said tip 21 is so adjusted in practice that until the filling-mass within the shuttle approximates the predetermined minimum 35 the forward push of the periphery of such mass against the end-surface 71 of the filling-feeler member 8 will carry both members 8 and 18 forward without contact of the datum-surface of the shuttle with the tip 21. Also, so that after the diminishing diameter of the residue of said filling-mass permits contact of the datum-surface with the said tip, the resulting turning or revolving movement of the member 18 around its 40 pivot 19 will not be sufficient to withdraw controller-bolt 30 far enough to cause latch 33 to move into position to be engaged by the actuator 37 therefor until the said residue has become reduced to the predetermined 45 minimum.

The controller-bolt 30 aforesaid, by means of which the latch 33 of the change-calling mechanism is controlled vertically, extends transversely of the loom, and occupies a bore 50 41 in a small stand 31 fixed on breast-beam 32 closely adjacent the latch 33. As usual, the said latch is pivoted at 34 to the up-standing arm 35 fixed on the controller-rockshaft 36, which extends transversely 55 across the loom and is connected with the other members of the change-calling mechanism (not shown). The latch 33 is shown mounted as heretofore to overhang the oscillating weft-hammer 37, which latter is 60 employed as an actuator, as usual in prac-

tice, and so that when the latch is allowed to drop it will be engaged by the shoulder 38 of the weft-hammer as the latter moves forward, and thereby be driven forward to rotate controller-rockshaft 36 to call the 70 change.

The forwardly extending arm 24 of lever 18 is combined operatively with the controller-bolt 30, in this instance by means of a shackle 26 and wire 25. The said 75 shackle is connected pivotally to the said arm by means of a depending pin 27 carried by the shackle, which is entered into one of several holes 28 in the said arm 24, the pin being secured within the hole into which it is inserted by a cotter pin 271 below the arm. The shackle is in adjustable screw-threaded engagement with the outer end of the wire 25, a suitable lock-nut being employed, as at 261. The inner end 29 of the wire 25 is 80 turned down at right angles and hooked in a hole in the bolt 30, the said inner end being held in the said hole by a cotter-pin 291. The purpose in having several holes 28 in the forwardly extending 85 arm 24 of the lever 18 is to provide for giving the required amplitude of end-wise movement to the latch-controller bolt 30 by enabling the shackle 26 to be engaged with the said arm at different distances from the lever pivot 19. The length of the screw-threaded portion of connecting wire 25 is great enough to permit of such adjustment of the said wire and the shackle 26 with 90 respect to each other as may be required in order to vary the total length of the connections between lever 18 and bolt 30 to compensate for the range of adjustments of the 95 feeler-stand 11 transversely inward and outward necessary for placing the feeler-members 100 in proper working positions relative to the slot of the particular shuttle employed, and the filling-mass contained within such shuttle.

At 43 is the spring which serves to give the 105 datum-surface-engaging member its normal presentation position, and incidentally to give the controller-bolt 30 its normal position which holds the latch out of the path of the actuator. The said spring in this 110 instance is a contracting spiral spring having one end thereof engaged with a collar 45 that is fixed adjustably upon the wire 25, and the other end thereof engaged with a lug 44 of the bolt-guiding stand 31. In this 115 embodiment of the invention, the bolt coacts with the downturned portion of the wire 39, such wire having a screw-threaded stem that is screwed into a hole in the latch 33 and made fast by a lock-nut 42, the said downturned portion having its extremity bent to 120 extend fore-and-aft, with a downwardly facing convexity for contact with the top of the bolt. In this instance the bolt is formed with a beveled end 60 that is adapted to 125 130

raise the latch as the bolt is moved longitudinally inward by the action of the spring 43, the bolt serving when in its normal inward position to keep the latch elevated, as shown best in Fig. 5. A stop-pin 47 carried by the bolt 30 engages with the outer end of the stand 31, so as to limit the inward movement of the bolt 30 under the pull of the spring 43.

10 Normally the controller-bolt 30 is held by the spring 43 in the position represented in Figs. 1, 2, 5, and 6, in which it supports the latch 33 in the elevated position that is shown in Fig. 4, with its engaging end out 15 of the path of the shoulder 38 of the actuator 37. When the lever 18 is rotated around its pivot 19 through action of the datum-surface on the shuttle against the tip 21, the controller-bolt is withdrawn from under the 20 wire 39 so as to permit the latch 33 to drop into the path of shoulder 38. The downwardly facing convexity of the lower portion of the wire 39 enables the wire to ride up on the inner end of the controller-bolt 25 30 as the latch goes rearwardly with the rearwardly swinging actuator 37, after having been advanced by the forward stroke of said actuator, the controller-bolt having been permitted to resume its inward position 30 under the action of the spring 43 as the lay swings rearward and relieves the pressure of the datum-surface against tip 21.

The feeler-stand 11 in this instance is mounted upon a forward extension 50 of a 35 supporting arm 51 which is attached by bolts 53, 53, to a bracket 55 extending outward from the breast-beam 32. Fore-and-aft adjustment of the feeler-stand is provided for, as usual in practice, by means of a 40 slot 48 in the feeler-stand 11 occupied by a bolt 49 which holds the stand to said extension 50. As usual, also, adjustment of the feeler-stand transversely of the loom is provided for by means of transversely extending slots 52, 52, occupied by the bolts 53, 53, aforesaid, which hold the supporting arm to the said bracket 55 projecting outward from the breast-beam 32. The capacity for transverse adjustment enables the 45 feeler-stand to be given a position which will enable the feeler-members to enter the

slots 59 and 61 in the front-plate 5 and shuttle body, respectively, and the fore-and-aft adjustment provides for setting the feeler-stand so that the feeling action of the feeler-members shall take place at the proper point in the advancing movement of the lay.

55 What is claimed as the invention is:—

1. In filling-feeler mechanism for looms, comprising an actuator, a latch adapted to 60 be engaged thereby, and a feeler-member adapted to be engaged by the shuttle contents, the combination therewith of a datum-engaging member moving forwardly and rearwardly with the said feeler-member and adapted to swing transversely in a horizontal plane when acted upon by the datum-surface, an endwise movable bolt linked to said datum-engaging member and through its 65 endwise movement controlling the position 70 of the latch vertically with relation to said actuator, and a spring by which said bolt and datum-engaging member are held in their normal positions.

2. In filling-feeler mechanism for looms, 75 the combination with an actuator, a latch adapted to be engaged thereby, a filling-feeler member, and a datum-engaging member, pivotally mounted upon said feeler-member, of an endwise movable bolt linked 80 to the said datum-engaging member and through its endwise movement controlling the position of the latch vertically, and a spring holding said bolt and datum-engaging member in their normal positions. 85

3. Filling-feeler mechanism for looms comprising, in combination, an actuator, a latch adapted to engage therewith, a feeler-member adapted to engage the shuttle contents, a bell-crank pivoted upon said feeler-member having one end adapted to be engaged by a datum-surface, and a controller combined with the said bell-crank comprising a longitudinally reciprocable transversely movable bolt which at one extreme of its 90 endwise movement holds the latch normally raised out of engagement with the weft-hammer and in being withdrawn when the bell-crank is rotated through contact with the shuttle wall lets the latch drop into engagement with the weft-hammer. 95 100

SIMEON S. JACKSON.
